DESIGN FOR A COMPACT

Pearl Harper, Los Angeles, Calif.

Application December 11, 1944, Serial No. 116,825

Term of patent 7 years

(Cl. D86—10)

To all whom it may concern:

Be it known that I, Pearl Harper, a citizen of the United States residing at Los Angeles, in the county of Los Angeles and State of California, have invented a new, original, and ornamental Design for Compact, of which the following is a specification, reference being had to the accompanying drawing, forming a part thereof.

Fig. 1 is a top perspective view of a compact in open position, showing my new design;

Fig. 2 is a top plan view thereof in closed position;

Fig. 3 is a front elevational view thereof on a slightly enlarged scale;

Fig. 4 is an enlarged longitudinal sectional view taken on line 4—4 Fig. 1.

I claim:

The ornamental design for a compact, as shown.
PEARL HARPER.
